UNITED STATES PATENT OFFICE.

OSCAR S. FIELD, OF ROSELLE BOROUGH, NEW JERSEY.

LIGHT SIGNAL.

Application filed June 30, 1924. Serial No. 723,225.

This invention relates to an improvement in light signals such as are used for daylight indications on railroads. In practice it has been found that in order to satisfactorily project a beam of light in the daytime, it is necessary to have very accurate focusing of the light emitting device, and it is also necessary to be able to accurately align the beam along the path of travel of the vehicle which is to be signaled. It has also been found that it is necessary to set up a multiplicity of combinations of colored lights to convey the various information necessary in railroad operation and it therefore becomes desirable to have a light signaling system which is flexible and which will be adaptable to the various light combinations necessary.

The present invention has been produced with these problems in mind and will accomplish the above enumerated objects together with other desirable objects, which will more clearly appear in the accompanying specification and claims.

Referring to the figures, I have shown in Figure 1 a vertical cross section of a light unit which is a part of the complete signal. In Figure 2 I have shown in isometric projection, an assembly of three of these light units in a vertical row, this being one of the desirable forms in railroad work.

Figure 3 is a rear view of the light unit with the cover removed, Figure 4 is a horizontal section through the same, and Figure 5 is a detail view illustrating a portion of the unit.

Similar reference characters refer to similar parts in each of the several views.

From a general inspection of the figures, it will be apparent that I have provided a self-contained light projecting unit which may be built up into clusters or combinations of various forms as desired by setting the light units in different types of backgrounds which have apertures provided to accord with the formation of the lights that is found necessary.

I will now briefly describe the light unit itself and then describe how it is assembled into the completed signal unit.

Referring first to Figures 1, 3 and 4, the light unit consists of a case 1 which is provided with a partition 2 having an annular recess 3 which is adapted to carry an inner lens 4, properly held in place by means of supporting clips 5 and screws 6.

The front end of the case 1 is further pro-

vided with a recess 7 adapted to carry an outer lens 8 which is held in place by means of the hood ring 9. The hood ring 9 is equipped with a hood 10 (see Figure 2) which acts as a shield for the lens and prevents light from striking the surface of the lens and being reflected in a downward direction. The lenses 4 and 8 form what is known as a doublet combination, which has a focal point at 11 and is of such a character that when a source of light is placed at this focal point it will project a substantially parallel beam of light as indicated by the dot and dash line 12. It is apparent that the color of the beam of light projected may be readily modified by properly tinting the inner lens 4.

The case 1 is further provided with a supporting device for an electric lamp 13 which comprises a stud 14 rigidly mounted in the case 1 and locked therein by means of nut 15. Stud 14 is threaded through its entire length and a carrier member 16 is adapted to freely slide over this stud. The carrier member 16 is provided with a slot 17 into which is inserted a knurled nut 18, which is adapted to fit threaded stud 14 and snugly fit the slot 17. It will be apparent from this construction that carrier member 16 is supported on stud 14 in such a manner that it may be freely rotated around the same or may be raised or lowered by rotation of the nut 18. A knurled nut 19 is provided to lock the member 16 on stud 14 in any desired position. Carrier member 16 has a second stud 20 mounted therein in such a manner that it may freely slide therethrough in a horizontal plane as shown. The stud 20 is provided with keyway 21 and is prevented from rotating in carrier member 16 by means of a set screw 22 passing through member 16 into keyway 21. A further slot 23 is provided in carrier member 16 in which knurled nut 24 is inserted, this nut being adapted to fit the thread on stud 20 and snugly fit in the slot 23. It will be seen that by rotation of the nut 24, the stud 20 may be caused to travel backwards or forwards in accordance with the direction of rotation of the nut and may be properly locked in any position by means of a knurled nut 25 as shown. The stud 20 is provided with a supporting bracket 26 which carries a suitable type of

light socket 27 adapted to hold the electric lamp 13 in such a manner that its filament

28 approximately coincides with the focal point of the lens combination. It will be seen by this combination of parts that I have provided a means whereby the filament 28 may be readily moved in any plane, thereby making it possible to accurately locate the filament on the focal point of the lens combination. In order to be able to determine when the filament coincides with the focal point, I have provided sighting devices, one device being adapted to check the location of the filament on the focal axis of the lens combination, the other device being arranged to determine the proper location 10 of the filament along the focal axis of the lens combination. The device for determining the location of the filament on the axis consists of a member 29, arranged to fit over the thread of stud 14 and after being 15 properly located thereon, locked in place by means of nut 30.

Member 29 is provided with a shield 31, adapted to protect the eye from the glare of the filament 28 and is also provided with a 25 telescopic peephole 32, through which the filament may be viewed. This peephole is of sufficient length to properly align the filament therethrough and is adjusted to coincide with the focal axis of the lens combination. It will be seen that while looking 30 through this sight, the filament may be moved either horizontally or vertically until it can be seen in the center of the peepsight, and it will then be properly located on the focal axis of the lens combination. After 35 this operation is completed, the carrier member 16 is locked in position by means of the nut 19, thereby rigidly locking the filament on the focal axis.

40 In order to check the position of the filament along the focal axis, I have provided a second sighting device which comprises an elongated member 33 which is equipped with an adjustable shutter 34 at the outer 45 end of the member 33. This shutter has a small aperture 35 approximately through its center. A surface disposed at an angle of 45° to the shutter 34 is provided and is preferably colored white.

50 Across the surface at 36, a vertical line is provided preferably black, to obtain maximum contrast to the white surface. This surface can be viewed from the rear of the light unit through aperture 37 in the member 33, as can be clearly seen by reference 55 to Figures 3 and 4. The member 33 is supported in case 1 by means of stud 38 and nuts 39 and is arranged to project horizontally across the light unit at right angles 60 to the focal axis of the lens combination. It will be seen by this structure that I have virtually provided what is known as a pin hole camera and that an image of the filament 28 will be projected on the white surface 65 36. After shutter 34 has been properly

adjusted it is permanently locked in position by means of a drop of solder. When the filament 28 is at its proper location along the focal axis of the lens combination, the image of the filament projected will accurately straddle or coincide with the vertical black line 36, thereby indicating to the operator that he has moved his light into the focal point of the lens combination. After the lamp has been properly focused, 70 lock nut 25 is tightened and the focusing operation of the light unit has been completed.

Case 1 is provided with an aperture 40 through which wires may be brought to the 80 lamp and is further provided with a proper cover 41 adapted to shed the rain and provided with a hasp 42 and staple 43, so that the cover may be locked in place.

In order to properly mount the unit in 85 light signal combinations, all that is necessary is to furnish suitable backgrounds or supports. In Figure 2, I have indicated, at 44, one form of background which may be used, being adapted to support three of the 90 light units in a vertical row. While this particular form is shown, it is apparent that a multitude of other forms may be made and any combination of lights set up.

The light units are mounted on the background 44 by means of adjusting screws 45, 46, 47 and 48 respectively. It will be seen that these screws are arranged to be threaded into the background 44 and that the screws 47 and 48 are passed through the rim 49 and the case 1 into the background, and that the screws 45 and 46 pass through the background and are in intimate contact with the back surface of the rim 49. By this arrangement it is apparent that by backing off screw 46 and moving screw 45 forward, the light unit may be tipped downward, causing it to project its beam in a downward direction, or by reversing the operation, the beam may be elevated. In a like manner, by similarly manipulating the screws 47 and 48, the beam may be moved in a horizontal plane. After the light unit has been properly aligned, screws 45, 46, 47 and 48 are locked by means of lock nuts 50, thereby rigidly holding the light unit in its position.

In order that the operator may properly determine where the beam of light is being projected, a telescopic sighting device is provided on each light unit. Referring now also to Figure 5, this device comprises an extension lug 51 outstanding from the case 1 and having a small peephole 52 therein. Co-acting with this lug in the front rim 49 of the case 1 is an aperture 53 so arranged that the axis of the aperture 53 and of the peephole 52 are parallel to the focal axis of the lens combination in the light unit, and are of such dimensions that they represent the spread or angle of di- 120 125 130

vergence of the light beam, usually about 6° in practice. It will be apparent that the light unit will be properly adjusted when the point or point towards which it is desired to direct the signal beam are visible through the peep hole 52 and the aperture 53.

From the above description it will be seen that I have provided a self-contained light unit which is fully equipped with adjusting and sighting devices to make it entirely independent of any other light unit, together with means of mounting this light unit in frames to form desirable signal combinations. While I have shown one specific design and form of light unit and mounting, it is apparent that various modifications may be made without departing from the spirit of the invention.

20 What I claim is:—

1. A light signal comprising a case, a source of light in said case, optical means supported by said case for projecting a beam of light from said source, a first stud rigidly attached to said case, a carrier member provided with a hole freely receiving said stud, means for locking the carrier member in adjusted position with respect to said first stud, a second stud attached to said light source and mounted in said carrier member for movement relative thereto at right angles to said first stud, means for locking said second stud in adjusted position with respect to said carrier member, and sighting means receiving light from said source whereby said source may be accurately located at the focal point of said optical means, a portion of said sighting means being supported on said first stud.

40 2. A light signal comprising a case, a source of light in said case, optical means supported by said case for projecting a beam of light from said source, a first stud rigidly attached to said case, a carrier member provided with a hole freely receiving said stud, means for locking the carrier member in adjusted position with respect to said first stud, a second stud attached to said light source and mounted in said carrier member for movement relative thereto at right angles to said first stud, means for locking said

second stud in adjusted position with respect to said carrier member, and a sighting device mounted on said first stud for determining when said source occupies a predetermined position with respect to said optical means.

55 3. A light signal comprising a case, a source of light in said case, optical means supported by said case for projecting a beam of light from said source, a first stud rigidly attached to said case, a carrier member mounted on said stud, and arranged to move longitudinally on said stud and to swing about the stud as an axis, means for clamping said carrier member in adjusted position with respect to said first stud, a second stud provided with a keyway and passing freely through said carrier member, a set screw in said carrier member and entering said keyway to prevent rotation of said second stud, 60 means for clamping said second stud in adjusted position with respect to said carrier member, and means on said stud for supporting said light source.

65 4. A light signal comprising a case containing a source of light, a lens fitted in said case for projecting a beam of light from said source, a stud rigidly attached to said case, means mounted on said stud for supporting said light source and permitting adjustment 70 thereof in three planes, and a sighting device supported by said stud and disposed on the optical axis of said lens for determining when said light source lies in said axis.

75 5. A light signal comprising a case, a source of light in said case, a lens supported by said case for projecting a beam of light from said source, a stud rigidly attached to said case, means mounted on said stud for supporting said light source and permitting 80 adjustment thereof in three planes, a first sighting device mounted on said stud with its axis disposed in the optical axis of said lens, and a second sighting device mounted in said case and having its axis at right 85 angles to the axis of said first device and intersecting the axis of said first device at the focal point of said lens.

In testimony whereof, I have signed my name to this specification.

OSCAR S. FIELD.
